UNITED STATES PATENT OFFICE.

ARTHUR J. MOORE, OF KENWOOD PARK, IOWA.

GAME-BOARD.

1,240,756.

Specification of Letters Patent. Patented Sept. 18, 1917.

Application filed December 1, 1915. Serial No. 64,515.

To all whom it may concern:

Be it known that I, ARTHUR J. MOORE, a citizen of the United States, residing at Kenwood Park, in the county of Linn and 5 State of Iowa, have invented new and useful Improvements in Game-Boards, of which the following is a specification.

My invention relates to game tables and the invention consists of a novel and improved game table involving new details and the peculiar arrangement thereof which I will now proceed to describe with reference to the accompanying drawing forming a part of this specification and in which— 15 Figure 1 is a top plan view of the game table or board.

Fig. 2 is a cross section thereof.

Fig. 3 illustrates the men or pieces used in playing the game of Marketing; and

20 Fig. 4 is a view illustrating a few of the men or pieces used in the game of Spello, there being 26 of these pieces.

Referring to the drawings, the numeral 1 designates the body of the board which is 25 of hexagonal shape in plan. At its center the board is provided with a hexagonal shaped figure 2 having displayed therein the names of different commodities such as oats, rye, pork, wheat, and barley. The corners of this hexagonal figure are connected to the corners of the edge of the board, which, is also preferably of hexagonal shape, by means of the lines 3. By this arrangement the top surface of the board is 30 divided into playing areas, each area being sub-divided into squares that are consecutively numbered from 1 to 105. The line 3 extends inwardly at a distance great enough to intersect a circle arranged within the 35 hexagon and each of the arcs thus formed is sub-divided into equal spaces by means of the numerals which are indicated by the reference character 4. These numerals range from 1 to 10, every third numeral being 40 duplicated and of a contrasting form from the remaining ones, as shown, for a purpose hereinafter described. Coöperating with these numerals is a pointer 5 operating in the well known manner. At the 45 present time there are three or more games which can be played upon the improved board, entitled as follows; "Market", "Spello" and "Six Checks".

In playing the game "Market" there are 50 six men or pieces for each player, each piece being marked in the manner shown in Fig.

3 to correspond to each of the playing areas upon the board. In starting the game the indicator is set into operation, the number opposite which the pointer stops indicates 60 the number of points the operator is to advance in his particular area, for example, the pointer stops opposite the numeral 5 the player would advance his piece five squares or blocks. As above stated every third 65 number is duplicated and has a contrasting form, this contrasting number being the 4th number and should the pointer stop opposite this number the player is set back that number of points and his piece is therefore 70 moved accordingly. As each of the pieces are named to correspond to commodities of the different areas, should the pointer stop within the section indicated by rye the rye piece is used and should the pointer stop 75 within the corn area the corn piece is used. As the play advances the number that each commodity has gained is recorded, the playing continuing until one member has succeeded in placing all of his men or pieces 80 in the center block. The numbers then recorded are counted and the player which has the highest score or most points wins the game.

In the game of Spello, the circle in the 85 center is not used, the play being confined to the triangular areas in the circle and the outer edge of the board. In playing this game the men or pieces which are used are illustrated in Fig. 4 and consist of 26 men, 90 each being supplied with one letter of the alphabet. These men are placed on the black squares, the one having the letter "A" being placed in the left hand square nearest the circle, that is, the square number 102 95 and continued in alphabetical order backward and forward within the triangular area until the entire number of men have been placed. One of the players then selects a word, or if desired more than one 100 word and the men or pieces are then moved over the board diagonally as in checkers, each player taking his turn around the board until the proper letters are placed on the outer edge of the board to spell the word 105 or words selected. The player getting the word correctly spelled first, wins the game. As some words have duplicate letters, the reverse side of the men may have letters placed thereon, in order that they may be 110 turned over to supply those needed.

The game of Six Check is played upon

the triangular areas used for the game of Spello previously described. In this game eight men or pieces are used by each player, the number of persons playing the game 5 ranging from one to 6. The men used by each player are of a different color, and as the game is capable of being played by six persons there will be 48 men or pieces of 6 different colors. These men may be made 10 of any shape, such as checkers, or any material and for this reason it is not thought necessary to illustrate them, it being only necessary that each player be provided with eight men of a distinguishing color from the 15 remaining players. The players start in opposite pairs, after placing their men in any position upon the black squares of their respective areas. One player of each pair moves to the right and the other to the left 20 around the board, each trying to cross the heavy line which divides the triangular areas, but always keeping on the black squares, and trying to prevent the opponent from jumping his men and removing them 25 from the board as in checkers. After the first pair of players have moved one space, the opposite pair to their right will then move, and as previously stated each moving in an opposite direction. The men or pieces 30 are to be kept moving in a forward direction around the board, but may be moved either in the direction of the inner circle, or the outer edge of the board, each pair of players moving simultaneously in their turn. After 35 two opposite opponents have succeeded in moving all of their players past one another,

they may then move around the board to meet the men of the other players in the game. At this stage of the game the players which have passed each other can then move 40 their men in any direction desired, the object being to get as many players in the circle in the center of the board as possible, the player getting the most men in the circle 45 winning the game.

Having described my invention what is claimed is:

1. A game board having a surface divided into a plurality of individual playing areas, each of said areas being divided into squares 50 of different consecutive values, a central circle divided into arcs, indicia for each of said arcs for indicating the values of the plays, pieces movable over the said areas and means carried by the board for determining 55 such movement.

2. A game board of hexagonal shape having an inner circular space provided with indicia, lines connecting the corners of the board with the inner circular space to provide divisions for said indicia, said lines forming independent playing areas, said areas being divided into squares over which the pieces move and a pointer coöoperating 60 with the indicia for determining the value 65 of each play.

In testimony whereof I affix my signature in presence of two witnesses.

ARTHUR J. MOORE.
